(57) **CLAIM**

The ornamental design for a hard drive enclosure, as shown and described.

DESCRIPTION

FIG. 1 is a perspective view of a hard drive enclosure, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

Unshaded surfaces seen in FIGS. 1 and 3 describing the inner surfaces of the small oval features on the front of the design form no part of the claimed design.

Broken lines seen in the drawings depict portions of the hard drive enclosure that form no part of the claimed design.
